UNITED STATES PATENT OFFICE.

CHARLES A. FRENCH AND RUSSELL E. WATERMAN, OF LONG BEACH, CALIFORNIA, AS
SIGNORS TO FARMERS NATIONAL BANK, TRUSTEE, OF GREENVILLE, OHIO, A COR-
PORATION OF OHIO.

AUTOMATIC FUEL-REGULATING DEVICE FOR STEAM-POWER PLANTS.

Application filed November 25, 1924. Serial No. 752,274.

Our invention relates to regulating devices, and more particularly to a device for automatically regulating the fuel supply to the main fire of the hydrocarbon burner of 5 a steam boiler.

The general object of our invention is to provide a steam-pressure operated regulating device for regulating the main fire and heat 10 of the hydrocarbon burner of a steam boiler to maintain the steam pressure in said boiler between predetermined limits.

A more particular object is to provide a regulating device of this class for regulating the supply of fuel from a carburetor 15 simultaneously with the control of the air to a burner.

A further object is to provide a regulating device which will be positive in its action and which will effect complete opening and 20 closing of the fuel supply valves to a burner.

With these and other objects in view as will appear hereinafter, our invention consists of certain novel features of construction, combination and arrangement of parts 25 and portions, as will be hereinafter described in detail and particularly set forth in the appended claims, reference being had to the accompanying drawings and to the characters of reference thereon, which form a 30 part of this application, in which:

Figure 1 is a front view of our regulating device with the cover removed and showing by dotted lines the air valve closed; Fig. 2 is a vertical longitudinal section of our 35 regulating device taken on line 2—2 of Fig. 1 and showing certain parts and portions in elevation to facilitate the illustration and showing the air valve open; Fig. 3 is a vertical section of the supply valve to the 40 burner taken on line 3—3 of Fig. 2 showing the fuel and air valves open; and Fig. 4 is a view similar to Fig. 3 with fuel and air valves shown closed.

Like characters of reference refer to 45 similar parts and portions throughout the several views of the drawings.

Referring in detail to the drawing, 1 indicates a casing closed by a cover 2 which is secured on the front of the casing by bolts 3. 50 On the rear wall of the casing 1 near the bottom of the casing is formed an internal embossment 4 through which, and the rear wall extends a bolt 5, the head 6 of which bolt being on the inner end thereof. A ball bear-

ing 7 fits on the inner end of the bolt 5 and a 55 nut 8 screws on the outer end of the bolt against the outside of the rear wall of casing 1 whereby the head 6 of the bolt is caused to hold the ball bearing 7 against the inner end of the embossment 4. The outer ring 60 of the ball bearing 7 is secured in the lower end of a balancing arm 9 so that said arm turns on said bearing. A segmental gear 10 is formed on the upper end of arm 9 and meshes with a pinion 11 secured on the inner 65 end of a shaft 12 within the casing 1, which shaft projects rearwardly through an opening 13 in the rear wall of said casing and extends transversely within a burner air duct 14 and is journaled in a bearing 15 in the 70 wall of said duct. A valve member 16 is secured on the shaft 12 in the duct 14. The duct 14 leads into a burner (not shown) which burner may be located under a steam 75 boiler. The lower portion of the arm 9 is formed with a pair of shoulders 17 and 18 at opposite sides of the bolt 5 or fulcrum of the arm, on which shoulders rest hardened steel seat blocks 19 and 20 respectively, there being dowels 21 and 22 depending from said 80 seats respectively into bores 23 and 24 in said shoulders respectively whereby said seats are held on said shoulders. Lugs 25 and 26 project from the lower portion of the shoulders 17 and 18 respectively for respectively engaging the upper ends of set screws 85 27 and 28 seated in the lower wall of the casing 1 whereby the rocking movement of the arm 9 is limited in either direction. Lock nuts 29 and 30 are fitted on the set 90 screws 27 and 28 for engaging the lower wall of the casing for locking said screws in adjusted positions. The seat blocks 19 and 20 are formed in their upper faces with knife edge seats 31 and 32 respectively. 95

Angle hangers 33 and 34 are bolted by bolts 35 and 36 to the rear wall of the casing 1 in the upper part of said casing. The hanger 33 is formed with an arcuate flange 37 at its lower edge, the curvature of which flange being an arc described from the knife edge seat 31 as a center. Said flange 37 is provided with a slot 37^a. The hanger 34 is formed with an arcuate flange 38 at its lower edge, the curvature of which flange being an 100 arc described from the knife edge seat 32 as a center. The flange 38 is provided with a slot 38^a. 105

A steam pressure actuated corrugated copper expansion means 40, commonly known as a sylphon, is formed at its upper end with an adjusting head 41 which is adjustably secured to the flange 37 by a bolt 42 extending through the slot 37^a in said flange whereby the expansion means is adjustably secured in position with its axis extending through the knife edge seat 31. The expansion means 40 is encased in a cylindrical guide 43 and bears at its lower end against the lower end 44 of said guide which lower end is formed with a depending hardened steel knife edge 45 which rests in the knife edge seat 31. The adjusting head 41 is formed with a pipe connection 46 and with a duct 47 leading from said pipe connection into the expansion means 40. A pipe 48 is connected to the pipe connection 46.

A spring 50 rests at its lower end upon a seat 51 and bears at its upper end against a spring adjusting head 52. The seat 51 is formed with a hardened steel knife edge 53 which rests in the knife edge seat 32. Said seat is also formed with an upstanding guide rod 54 which extends upwardly through the spring 50 and into a tubular guide member 55 depending from the adjusting head 52. The spring adjusting head 52 is adjustably secured to the under side of flange 38 of hanger 34 by a bolt 56 which extends through slot 38^a.

To the valve 16 is secured an arcuate fuel valve member 60 provided with an opening 61 which valve member extends across the discharge end of a carburetor air balancing pipe 63 which projects into the duct 14.

The operation of my regulating device is as follows:

When the pressure is normal the arm 9 inclines to the left and the valve is open when the pressure runs high said arm swings to the right as shown in Fig. 1 and the valve is closed. Steam boiler pressure is conducted through pipe 48 and duct 47 into the expansion means 40 which, when a predetermined pressure is reached expands the means 40 downwardly, and the lower end of the expansion means, engaging the lower end wall 44 of the guide 43, forces said guide downwardly as shown in Fig. 1. The downward movement of the guide, through the engagement of knife edge 45 with seat 31, swings the balancing arm 9 to the right against the tension of the spring 50, and such movement of the balancing arm, through the segmental gear 10, pinion 11, and shaft 12, swings the valve 16 closed which stops air passing through the duct 14 to the burner. The carburetor air balancing valve 60 covers and closes the end of the carburetor air balancing pipe 63 except when the air valve 16 is fully open, in which position of the air valve the port 61

of valve 60 registers with the end of the pipe 63. This prevents the pipe 63 receiving the velocity head of air in duct 14 except when the valve 16 is fully open. The difference between the static and velocity heads may be used to cause fuel to flow into a fuelizer (not shown) from a carburetor (not shown).

As the balancing arm 9 is swung to the right by the expansion means to close the valve, the leverage of the expansion means upon the balancing arm increases while the leverage of the spring 50 decreases, thus causing the valve to be rapidly and fully closed and to be held closed until there is a definite drop in the boiler pressure and the power of the spring with its decreased leverage upon the balancing arm overcomes the power of the expansion means and its increased leverage upon the balancing arm, whereupon the balancing arm is swung to the left and valve 16 opened. The valve remains open until the boiler pressure rises to the original predetermined closing point.

Upon loosening the nuts 42 and 56 the adjusting heads 41 and 52 may be shifted on the flanges 37 and 38 to vary the leverage of the expansion means 40 and spring 50 upon the balancing arm whereby the range between opening and closing pressures may be varied.

Though we have shown and described a particular construction, combination and arrangement of parts and portions and certain modifications thereof, we do not wish to be limited to this particular construction, combination and arrangement nor to the modifications but desire to include in the scope of our invention the construction, combination and arrangement substantially as set forth in the appended claims.

Having thus described our invention what we claim as new and desire to secure by Letters Patent, is:

1. In a regulating device of the character as disclosed, a substantially upright balancing arm, a valve, gear and rack means whereby said valve is opened or closed by said balancing arm, pressure operated means acting upon said arm for swinging said arm to close said valve, and a spring acting upon said arm tending to open said valve.

2. In a regulating device of the character as disclosed, a substantially upright balancing arm, a valve, gear and rack means whereby said valve is opened or closed by said balancing arm, an expansion means connected to a source of steam pressure, a guide encasing said expansion means and engaging said balancing arm for swinging said arm to close said valve when the expansion means is expanded, and a spring acting upon said arm tending to open said valve.

3. In a regulating device of the character

as disclosed, a balancing arm, a valve, means whereby said valve is opened or closed by said balancing arm, an expansion means connected to a source of steam pressure, a 5 guide encasing said expansion means, a knife edge on said guide, a seat on said balancing arm engaged by said knife edge for swinging said arm to close said valve when the expansion means is expanded, and a 10 spring acting upon said arm tending to open said valve.

4. In a regulating device of the character as disclosed, a balancing arm, a valve, means whereby said valve is opened or closed by 15 said balancing arm, an expansion means connected to a source of steam pressure, a guide encasing said expansion means, a knife edge on said guide, a seat on said balancing arm engaged by said knife edge for 20 swinging said arm to close said valve when the expansion means is expanded, a spring seat, a knife edge formed on said spring seat, a seat on said balancing arm, in which 25 said knife edge rests, a guide rod on said spring seat, a spring head, a guide member on said spring head in which said guide rod reciprocates, and a spring between said 30 spring seat and spring head surrounding said guide rod and guide member, said 35 spring acting in opposition to said expansion means for opening said valve.

5. In a regulating device of the character as disclosed, a balancing arm, a valve, means whereby said valve is opened or closed by 35 said balancing arm, a pressure operated means applied to said arm at one side of

the fulcrum thereof for swinging said arm to close said valve, the leverage of said pressure means upon said arm increasing as the arm is swung by said pressure means 40 to close said valve, and a spring applied to the other side of the fulcrum of said balancing arm for swinging said arm to open said valve, the leverage of said spring upon said arm decreasing as the arm is swung by 45 the spring to open the valve.

6. In a regulating device of the character as disclosed, a balancing arm, a valve, means whereby said valve is opened or closed by said balancing arm, a pressure operated 50 means applied to said arm at one side of the fulcrum thereof for swinging said arm to close said valve, the leverage of said pressure means upon said arm increasing as the arm is swung by said pressure means to 55 close said valve, and a spring applied to the other side of the fulcrum of said balancing arm for swinging said arm to open said valve, the leverage of said spring upon said arm decreasing as the arm is swung by the 60 spring to open the valve and means for adjusting the positions of said pressure operated means and said spring to vary the leverage thereof upon said balancing arm to provide for a short or long range between 65 opening and closing pressures.

In testimony whereof, we have hereunto set our hands at Los Angeles California this 13th day of November, 1924.

CHARLES A. FRENCH.
RUSSELL R. WATERMAN.
